RAT-HOLE PACKER

Filed April 30, 1937

UNITED STATES PATENT OFFICE

2,172,948

RAT HOLE PACKER

John E. Weller, Duncan, Okla., assignor to Halliburton Oil Well Cementing Company, Duncan, Okla.

Application April 30, 1937, Serial No. 139,937

5 Claims. (Cl. 166—11)

This invention relates to oil well equipment and more particularly to means and methods for setting packers in a rat-hole in a well.

It is often desirable to effect a seal between a conduit placed in an oil well and the wall of the well. For example, where it is desired to obtain a sample of the connate fluid in the well by means of a testing tool, a packer is placed on the bottom of the tool to effect a seal. An example of this is disclosed in the patent to Simmons, No. 1,930,987. In making a test a cone packer is commonly employed and is seated upon a rat-hole or hole of small diameter in the bottom of the well. The shoulder at the top of the rat-hole sometimes crumbles so that it is difficult to effect a seal with a cone packer and other difficulties sometimes arise as, for example, where the rat-hole is not exactly centered with respect to the main part of the bore hole.

20 It is an object of the present invention to devise means and methods for setting a wall packer in the rat-hole in addition to the cone packer to effect a double seal.

It is another object of the invention to provide 25 means and methods for setting a wall packer in a rat-hole without employing an anchor pipe or other means below the packer for supporting it while it is being seated.

Other objects reside in certain novel features 30 of the apparatus and methods as will be more apparent from the following description taken in connection with the accompanying drawing, in which:

Figure 1 is a vertical cross-sectional view of 35 the lower portion of an oil well showing in vertical cross-section a cone packer and a wall packer in the rat-hole of the well, together with mechanism for setting the same; and

Figure 2 is a vertical cross-sectional view similar to Figure 1 but showing the parts in the relative positions which they occupy when the packers are set.

Referring to the drawing in detail, it will be seen that an oil well is there shown as provided 40 with a bore, hole 11 and a rat-hole 12, the top of the rat-hole providing a shoulder 13. The apparatus for effecting a seal in the rat-hole may be connected to the bottom of a testing tool or to other equipment (not shown) which is to 45 be sealed in the well. In the arrangement illustrated, two packers are employed, one consisting of an ordinary cone packer 14 and the other consisting of a wall packer 15.

To support the packers, a mandrel or operating member 16 is provided, the upper end of which is

screw threaded as shown at 17 to provide means for connecting it to a testing tool or a pipe. The mandrel extends downwardly through the cone packer 14 and is fastened to the upper shoe 18 of the wall packer 15 by means of a screw threaded 5 connection 19.

The upper shoe 20 of the cone packer 14 is connected to a sleeve 21 which is in turn connected to the lower shoe 22 of this packer, the shoes and the sleeve being screw threaded together so as to provide means for compressing the packer 14 and holding it firmly between the shoes. The assembly of the packer 14, shoes 20 and 22, and the sleeve 21, is mounted for limited longitudinal movement upon the mandrel 16 but 10 is prevented from rotating with respect thereto by means of a key 23 fitted into slots 24 in the mandrel 16 and secured to the upper portion of the sleeve 21. To prevent leakage through the slots 24, a sleeve 25 is screw threaded onto the 15 upper end of the sleeve 21 and provided with a stuffing box or gland 26 above the upper end of the slots 24.

The lower shoe 27 of the wall packer 15 is rigidly connected to the upper shoe 20 of the cone 25 packer 14. To make this connection, an inner sleeve 28 is screw threaded to the lower shoe 27 of the packer 15. This sleeve 28 passes upwardly through the mandrel 16 and is connected to the key 23 which, as mentioned above, is integral 30 with the sleeve 21 and the upper packer 20. The connection at the upper end of the sleeve 28 to the key 23 may be made by simply making slots in the sleeve 28 of the same size as the key and passing the key therethrough.

In addition to the packing gland 26 near the top of the mandrel 16, an additional packing gland 29 is provided between the lower shoe 22 of the packer 14 and the mandrel 16 to prevent fluid flowing upwardly between the sleeve 21 and the 40 mandrel and into the mandrel through the slots 24.

To effect a seal in the rat-hole 12 of the well, the apparatus is connected to a conduit and lowered into the well with the parts in the relative 45 position shown in Figure 1. The packer 14 is of sufficient diameter to prevent it entering the rat-hole while the packer 15 should preferably be but slightly smaller than the rat-hole so that it may be set therein without having to be expanded 50 very much.

When the packers are lowered into the rat-hole the cone packer 14 will rest upon the shoulder 13 and will thus constitute an abutment supporting the lower shoe 27 of the wall packer 15 55

since, as mentioned above, the shoe 27 is connected to the upper shoe 20 of the cone packer. Thus it will not be necessary to use an anchor pipe to support the shoe 27 of the wall packer in order to be able to set this packer. As the cone packer is forced into the rat-hole the mandrel 16 and the upper shoe 18 of the wall packer 15 will move downwardly, the parts then taking the relative positions shown in Figure 2. The downward pressure necessary to set the wall packer 15 will be considerable and this pressure will also be transmitted through the inner sleeve 28 to the upper shoe 20 of the cone packer so as to force the cone packer firmly into position. In this way a double seal is effected and even if the shoulder 13 is irregular in shape the wall packer 15 will prevent mud or other fluid in the well from flowing downwardly and passing up through the sleeve 28 and the mandrel 16 into the conduit to which it is connected.

In its broader aspects, the invention may be considered as providing means for setting a wall packer in a rat-hole without the use of a cone packer. A suitable block or other supporting means may be substituted for the cone packer 14 and act merely as an abutment for supporting the lower shoe of the wall packer without attempting to effect a seal on the shoulder 13.

Where the term "wall packer" is used herein, a hollow cylinder of rubber or other expansible material is meant, this cylinder being designed to effect a seal in an open hole rather than in casing or pipe in the hole.

Where the term "rat-hole packer" or "cone packer" is used herein, a hollow segmental cone of fabric, belting, rubber or like material is meant, this being designed to effect a seal in an open hole at the top of a "rat-hole" or hole of small diameter drilled in the bottom of a well.

Various changes may be made in the construction or arrangement of the parts and in the methods employed for effecting a seal without departing from the spirit of the invention or the scope of the annexed claims.

I claim:

1. Apparatus for effecting a seal between a conduit and a rat-hole in an oil well or the like, which includes a cone packer, a wall packer located below the cone packer, each of said packers having shoes, means connecting the lower shoe of the wall packer to the upper shoe of the cone packer, means for connecting the con-

duit to the upper shoe of the wall packer whereby the cone packer may act as an abutment or support for the lower shoe of the wall packer while the upper shoe thereof is moved downwardly by the conduit to set the wall packer. 5

2. Apparatus for effecting a seal between a conduit and a rat-hole in an oil well or the like, which includes means adapted to rest on the shoulder formed in the well at the top of the rat-hole, a wall packer adapted to enter the rat-hole, means for supporting the wall packer on said means which rests on the shoulder and means for setting the wall packer while it is so supported. 10

3. Apparatus for effecting a seal between a conduit and a rat-hole in an oil well or the like including, in combination, a cone packer, a wall packer located below the cone packer, a support for the wall packer consisting of a device connecting the same to the cone packer and mechanism for setting the cone packer in the top of the rat-hole and the wall packer within the rat-hole beneath the cone packer. 15 20

4. Apparatus for effecting a seal between a conduit and a rat-hole in an oil well or the like including, in combination, a cone packer, a wall packer located below the cone packer, a support for the wall packer consisting of a device connecting the same to the cone packer and mechanism for setting the cone packer in the top of the rat-hole and the wall packer within the rat-hole beneath the cone packer, said mechanism including a mandrel extending through the cone packer and connected to the wall packer, said mandrel being operable by manipulation 35 of the conduit to set the wall packer.

5. Apparatus for effecting a seal between a conduit and a rat-hole in an oil well or the like including, in combination, a cone packer, a wall packer located below the cone packer and mechanism for setting the cone packer in the top of the rat-hole and the wall packer within the rat-hole beneath the cone packer, said mechanism including a mandrel extending through the cone packer and connected to the wall packer, said mandrel being operable to set the wall packer, and a member connecting a part of the wall packer to a part of the cone packer to cause the cone packer to support the wall packer against downward movement during operation of 40 45 50 the mandrel to set the wall packer.

JOHN E. WEILER.
